UNITED STATES PATENT OFFICE.

HOWARD CRUNDEN CLEAVER, OF LONDON, ENGLAND.

INTERNAL-COMBUSTION ENGINE.

1,144,027.

Specification of Letters Patent. Patented June 22, 1915.

Application filed November 29, 1912. Serial No. 734,163.

To all whom it may concern:

Be it known that I, HOWARD CRUNDEN CLEAVER, a subject of the King of Great Britain, residing at 35 Berners street, London, England, have invented new and useful Improvements in Internal-Combustion Engines, of which the following is a specification.

This invention relates to developments and improvements in engines wherein distribution is governed by a cylinder rotating within a fixed cylinder or between two fixed cylinders concentric therewith.

The engine of my invention is primarily intended for use as an internal combustion engine working on the Otto cycle principle but may be operated by other propulsive means such as by steam.

According to the present invention I provide a second port in the valve cylinder or sleeve and cause the sleeve to rotate at a $\frac{1}{2}$ engine speed, thus causing the two rotating ports to register alternately with the fixed cylinder ports the said fixed ports being constructed and arranged sufficiently near to each other to compensate for the slow rotation of said valve cylinder and I provide a second pair of ports in the fixed cylinders opposite to the first pair, thus providing duplicated passages for gases, by allowing the two rotating sleeve ports to register simultaneously with the two exhaust ports and subsequently with the two induction ports of the fixed cylinders.

It may be desirable to provide a third or further port or ports in the sleeve cylinder to register with the first pair of ports and a corresponding second or further pairs of ports in the fixed cylinder to register there-with simultaneously the rotational speed of the sleeve being reduced in the equivalent ratio but as far as my present experience goes two ports suffice in ordinary circumstances registering with two pairs of ports in the fixed cylinder or cylinders.

By means of the reduced rate of rotation of the sleeve valve cylinder friction is minimized and by means of the duplication or multiplication of ports the action of said valve cylinder is facilitated owing to the provision of increased port area permitting more perfect scavenging and alimentation especially at high speeds.

The walls of the rotating valve cylinder of my present invention are cut to give elasticity to the walls and they are grooved to assist lubrication. The said cuts in the

walls of said valve cylinder are preferably made to commence at the upper edge adjacent to the ports and to extend downward through the ports terminating a short distance below the port area. By this arrangement a force internally applied to the cut cylinder walls will expand them, thus when the force or explosion is so applied the said force will impinge upon the area of the rotating walls exposed by the ports of the fixed interior or piston cylinder and will thus cause the valve cylinder walls to bear more closely against the ports of the external cylinder thus effectively sealing the said ports at the desired moment. Further provision is made to maintain compression by the use of expansible rings which may be placed between the rotating valve cylinder and one or both of the fixed cylinders at any convenient point or points both above and below the port area and these rings may be of any convenient form or pattern.

The provision of improved lubrication is attained first by the construction of grooves preferably spiral on either or both sides of the sleeve valve cylinder and if desired alternatively or additionally on the sides of the fixed cylinders adjacent to the walls of the rotating cylinder in such a manner that the lubricating oil received upon one part of the cylinders may be raised or distributed rapidly over the whole frictional area. In addition I may cut, pierce or perforate any of the cylinder walls conveniently to allow the lubricating oil to pass through the openings thus formed from one side of the cylinder wall to the other side.

My invention is illustrated by way of example in the accompanying drawings in which—

Figure 1 shows a vertical section of an engine having an internal fixed cylinder. Fig. 2 shows a side elevation of a four cylinder engine partly in section. Fig. 3 shows a diagrammatic sectional plan view on a line A—B of Fig. 1. Fig. 4 shows a vertical section through the ports on the line C—D of Fig. 3. Fig. 5 shows a sectional plan view exposing the lay shaft on the line E—F of Fig. 1, and Fig. 6 a sectional view illustrating a modification of the valve structure.

Referring now to the drawings 1 indicates the fixed interior or piston cylinder, 2 indicates the rotating sleeve valve cylinder; 3 indicates the outer fixed cylinder incased

in a water jacket; 4 indicates the passage leading to the duplicate exhaust ports; 5 indicates the passages leading to the duplicate induction ports; 7 indicates the exhaust ports of the interior cylinder; 6 indicates the induction ports of said cylinder; 8 indicates the water space about the head of the cylinders; 9 indicates the toothed flange of the valve cylinders; 10 indicates the tooth members of a lay shaft 11 adapted to engage with the flanges 9; 12 indicates the transverse shaft used to operate the magneto; 13 indicates the piston.

Fig. 2 illustrates a chain drive 15 for operating the lay shaft 11 from the main shaft.

In Fig. 3 the relative positions of the ports of the rotating valve cylinders of a multi cylinder engine are illustrated, the rearmost cylinder (having both ports at right angles to the central line) being disposed at the moment of ignition and showing the amalgamation of ports in adjacent pairs in cylinders having contra rotation.

In Fig. 2 I illustrate the valve cylinder wherein 16 indicates a saw cut through the walls of the port area; 17 indicates the spiral oil grooves 18 indicates a perforation and 19 indicates a flange to receive the ball bearings 20.

In Fig. 6 I have illustrated a modified form of my invention, in which instead of a single rotating valve either disposed internally or externally with respect to a fixed piston cylinder, I may arrange a valve in the form of a pair of concentric cylindrical valve members 22 and 23, of contra rotation, as shown by the arrows, the walls of one valve member being in contact with the walls of the other. By this arrangement, I obtain a more rapid opening and closing of the ports of the engine. I provide in the outer cylindrical valve member 22 four ports 24, while in the inner cylindrical valve member 23 I provide two ports 25, of approximately twice the width of the said ports 24. During the contra rotation of said valve members, said ports are adapted to register with and open and close the corresponding pairs of ports 26 in the fixed cylinders 27 and 28. In Fig. 6 the valve is shown in the position of mid-exhaust.

It will be seen that by my construction and arrangement of parts (1) the working friction of the rotating cylindrical valve is reduced; (2) the action of said valve is facilitated by increased port area and by improved port action (3) an improved system of lubrication for the said cylinder is provided.

60 What I claim is—

1. In an engine the combination of a fixed interior cylinder having a plurality of pairs of ports, one port of each pair being an ad-

mission port and the other an exhaust port; a piston working in said cylinder; a main 65 shaft; crank connections between said piston and main shaft; an annular cylindrical valve sleeve mounted to rotate about said cylinder and having ports equal in number with the pairs of ports in said cylinder, adapted 70 when the valve is rotated to register alternately simultaneously with all the admission ports and then simultaneously with all the exhaust ports; and driving connections between said main shaft and valve sleeve for 75 driving the latter from the former at suitable relative speed.

2. In an engine the combination of a fixed cylinder structure comprising a pair of coaxial cylindrical shells spaced apart and 80 having a plurality of pairs of through ports leading through said shells one port of each pair being an admission port and the other an exhaust port; a piston mounted to reciprocate within the inner shell; a main shaft; 85 crank connections between said piston and main shaft; an annular cylindrical valve sleeve fitted to rotate in the space between the fixed cylindrical shells and having through ports equal in number with the 90 pairs of ports in said cylinder structure and adapted when the sleeve is rotated to register alternately simultaneously with all the admission ports and then simultaneously with all the exhaust ports; and driving connections between said main shaft and valve 95 sleeve for driving the latter from the former at suitable relative speed.

3. In an engine the combination of a fixed cylinder structure comprising a pair of coaxial cylindrical shells spaced apart and 100 having a plurality of pairs of through ports leading through said shells, one port of each pair being an admission port and the other an exhaust port; a piston mounted to reciprocate within the inner shell; a main shaft; 105 crank connections between said piston and main shaft; a pair of annular cylindrical valve sleeves mounted to rotate coaxially and in opposite directions in the space between said fixed sleeves, each sleeve having a plurality of ports adapted upon the rotation of said sleeves to register alternately 110 simultaneously with all the admission ports and then simultaneously with all the exhaust 115 ports; and driving connections between said main shaft and said sleeves for rotating the latter in opposite directions at suitable relative rates.

In testimony whereof I have signed my 120 name to the specification in the presence of two subscribed witnesses.

HOWARD CRUNDEN CLEAVER.
